G. A. Lovett

UNITED STATES PATENT OFFICE

JOHN M. LEA, OF DETROIT, MICHIGAN

FUEL-INJECTION SYSTEM

Application filed April 10, 1925. Serial No. 22,090.

The invention relates to means for supplying liquid under pressure to a point of utilization and, while in some respects of more general application, it is especially designed for, and will be herein described as adapted to, a system for supplying liquid fuel to the cylinders of an internal combustion engine.

Among the features which are involved in the invention are,

10 (1) The provision of means adapted to build up hydraulic pressure in an injecting device without motion except to the extent necessary to deliver a charge and to relieve such pressure without motion of the actuating device;

(2) The use of electromagnetic devices to produce the pressure necessary to force the liquid into the space to which it is to be supplied;

20 (3) The application of such devices to an engine cylinder so as to inject liquid fuel directly into the cylinder and preferably into proximity to an igniting device, as a spark plug;

25 (4) The provision of a power means independent of the engine for such injection which automatically meet and overcome the pressure conditions in the engine and subject to the control of a timing means;

30 (5) The control of the electromagnetic devices by the engine itself in such manner as to supply current for producing the required pressure automatically to an injecting device for each cylinder at the precise time when

35 fuel is to be injected;

(6) The control of the current-supplying means in such manner as to enable the operator to predetermine at will both the time of actuation of the injecting means relatively to

40 the phases or strokes of the engine and also the duration of the injection period whereby the quantity of fuel injected is affected;

(7) The control of the air supply to the engine in such manner as to utilize the suction produced thereby in the cylinder for drawing fuel through the injecting device for priming the latter and starting the engine;

(8) The provision of other control devices and accessories related to the principal features above mentioned.

The above and other objects and advantages will appear more fully from the following description taken in connection with the accompanying drawings in which

Fig. 1 is a side elevation of an engine showing my invention; 55

Fig. 2 is a section on line 2—2 of Fig. 1;

Fig. 3 is a sectional view of a nozzle;

Fig. 4 is a section on line 4—4 of Fig. 3;

Fig. 5 is a sectional view of an injector; 60

Fig. 6 is a section on line 6—6 of Fig. 7 showing details of a circuit making and breaking device;

Fig. 7 is a vertical section through the breaker assembly; 65

And Fig. 8 is a detail sectional view of a part of the injector mechanism.

Referring to the drawings, 10 indicates an internal combustion engine having a combustion chamber 11 including a cylindrical portion 11' in which operates a piston 12. Intake and exhaust manifolds 13, 14, are provided which communicate with the combustion space through the usual valves, one of the intake valves being shown at 15. Suitable igniting devices, as spark plugs 16, are mounted in proper position for igniting the mixture in the combustion space. The engine is shown as having four cylinders and the fuel supply devices are accordingly illustrated as 70 75 adapted to a four cylinder engine but it will be understood that the invention is applicable to any number of cylinders.

The engine illustrated includes a crank shaft 17 and cam shaft 18. The cam shaft 85 will be arranged to actuate the engine valves in the usual manner in accordance with which it will be rotated at half the crank shaft speed. These and other details of the engine, except as hereinafter described, may be 90 of any usual type and are therefore shown and referred to merely as conventional and simply to illustrate the application of the invention to such engine.

In the intake passage 19 leading to the 95 intake manifold 13, which serves in this case for the introduction of air to the engine cylinders, is mounted a valve 20 operable by a crank 21. This valve may be of the type commonly employed as throttle valves in 100

conventional throttle-controlled engines, and serves in connection with the present invention to restrict flow of air to the combustion chambers of the engine in order to produce therein a sub-atmospheric pressure whereby fuel may be drawn into the combustion chambers under certain conditions, as hereinafter explained.

Liquid fuel is supplied directly to each combustion chamber of the engine by a magnetically actuated injecting device which serves to exert pressure upon the fuel contained in a passage leading to a spray nozzle. This nozzle may be of any usual or suitable character but is shown as comprising a tubular casing 22 adapted to extend through the engine wall and preferably positioned to direct the injected fuel into proximity to the spark plug 16 to provide thereby a rich mixture in the vicinity of the igniting device whatever may be the condition elsewhere in the combustion chamber. The nozzle may be secured by engagement of screw threads 23 with a screw-threaded aperture in the engine wall. A supply tube 24 has its tip 25 secured to the outer end of the casing 22 by a screw cap 26. In the inner end of the casing is an aperture 27 within which is positioned a cylindrical projection 28 on the 30 end of a triangular plug 29. When liquid is supplied under pressure to the casing it flows past the plug 29 and is sprayed into the air through the narrow annular aperture around the projection 28.

The means for applying the pressure to the liquid supplied through the tube 24, shown in detail in Fig. 5, comprises a pumping device which is magnetically actuated and is preferably of the bellows type. The pumping chamber 30 is formed in part in the fitting 31 and in part in the metallic bellows member 32, the latter being capable of expansion and contraction to cause alternate periods of suction and pressure in the chamber. The tube 24 is secured to the upper end of fitting 31, as by screw cap 33, and communicates with pressure chamber 30. This communication is controlled by valve 34 seating on the inwardly flanged end of a cylinder 35 and pressed to its seat by a coiled spring 36 positioned between the valve and the inner end of cap 33. Liquid is supplied to the pumping chamber through a lateral bore 37 to which is fitted a pipe connection 38. Communication between the bore 37 and chamber 30 is controlled by a valve 39 similar to valve 34, and seating on the inwardly flanged end of cylinder 40. A spring 41, positioned between the valve and a screw plug 42, exerts pressure tending to seat the valve.

The bellows member 32 may be formed of a series of sections 43, 44, of sheet metal fitted together as shown in Fig. 8 and soldered or otherwise secured. The upper section is fixed

to the tubular head 45 which is screwed into the lower end of fitting 31. The lower section is fixed to the head 46 which carries a pin 47 having a shoulder 48 adapted to serve as an abutment to receive the thrust of an armature 49 whereby pressure may be exerted to cause contraction of the bellows. Means is provided to move the bellows in the opposite direction to cause expansion thereof, this means being preferably constituted by the bellows itself which may be given an initial "set", in such position that its inherent resilience tends to oppose the movement of the armature.

The armature 49 is pivotally supported at one end by balls 50, 51, seated in shallow depressions in the lower and upper faces respectively of the armature and resting against opposing faces of a channeled ring 52. The pivotal movement of the armature away from the magnet is limited by engagement of its free end with a suitable abutment, as with an adjustable stop 53 on the outer flange of the ring.

The armature is positioned adjacent to the lower end of core 54 which may be supported by screw thread engagement with the fitting 31. The core is surrounded by two windings, the inner one, 55, being connected at one end to conductor 56 through post 57. The other end may be grounded on the machine frame. The outer coil 58 is a secondary coil of fine wire which is merely short-circuited by connecting its ends to each other and serves to oppose the building up of electromotive force at the time when the circuit is broken in the circuit of coil 55, thereby reducing sparking at the terminals in the breaker hereafter described. The coils are retained on the core by a washer 59 at one end and insulated base plate 60 at the other, the latter serving also as a support for the ring 52. Suitable enclosing means is provided including the cup 61, clamped between the coil 54 and fitting 31, and a cover 62 screwed over the lower end of the cup, the cup and cover being preferably of magnetic material so as to provide an exterior magnetic circuit for the coil.

The supply of current to coil 54 to effect thereby the movement of armature 49 and the contraction of bellows 32 is controlled by a circuit making and breaking device shown in detail in Figs. 6 and 7. It includes a spindle 63 arranged to be driven in synchronism with the engine preferably by actuation by some moving part of the engine itself. As shown the lower end of the spindle extends into the crank case and is provided with a screw gear 66 meshing with a screw gear 67 on the shaft 18' which is driven by the cam shaft 18, the transmission ratios being such that the spindle is rotated at the proper speed to close the circuit to the coil 55 once for each cycle of operation of the engine. In a four

cycle engine, as illustrated, the fuel injection, of course, will occur once for each two revolutions of the crank shaft and hence the spindle should rotate at one half the crank shaft speed.

The upper end of the spindle is beveled on one side, the flattened surface extending inwardly toward the axis of the spindle at the top, thus providing a depressed cam surface 68 of gradually increasing extent toward the top. A casing 69 surrounding the upper end of the spindle encloses contact members 70 of a number equal to that of the injection devices to which current is to be supplied. In the present instance, the invention being shown as applied to a four cylinder engine, there are four of these contact members. The contact members are pivotally supported at 71 upon a conducting ring 72 which is insulated from the casing 69 by a washer 73. A binding post 74 connects the ring 72 to a conductor 75 leading to a suitable source of current, as the battery 76, (Fig. 1). The outer ends of contact members 70 carry contacts 77 adapted to engage with contacts 78 supported upon the insulating cap 79 and connected to the several leads 56 extending to the injector or pump coils.

At its inner end each contact member 70 carries a non-conducting button or contactor 80 in such position as to engage the periphery of the cam spindle 65, and suitable springs 81 are arranged to maintain the contactors in engagement with the spindle. The dimensions are such that when the contactor engages with the cylindrical portion of the spindle the contacts 77, 78, will be held out of engagement, whereas, when the contactor engages the flat or beveled portion 68, the contacts are permitted to engage for a period determined by the part of the cam with which the contactor engages.

In order to vary the time of engagement between contactor and cam, means is provided for adjusting the relative positions of the spindle and the contactors longitudinally of the spindle. By way of illustration I have shown an elbow lever 82 having one arm pivotally connected to a ring 83, fitting in an exterior circumferential groove in the casing 69, and having the other arm connected to an actuating rod 84 extending to any convenient location for manipulation by the attendant or operator. By actuation of the rod 84 the casing 69 may be raised or lowered thus varying the extent of cam surface 68 with which the contactors engage and correspondingly varying the duration of engagement of the contacts and of the application of pressure to the bellows 32 by the armature 49.

Means is also provided for varying the time when the contacts engage relatively to the phase of operation of the actuating means. This may be accomplished by varying the relative angular positions of the cam and con-

tactors and, in the embodiment illustrated, comprises a sleeve 85 surrounding the spindle 65 and rotatable relatively thereto. Sliding connection is provided, as by key 86, between the sleeve 85 and casing 69 so that the casing will be rotated with the sleeve but may be adjusted longitudinally on the sleeve as before explained. The sleeve 85 may be angularly adjusted in any suitable manner, as by the provision of a screw gear 87 on the sleeve meshing with the screw pinion 88 mounted on bracket 89 and operable by a shaft 90, (Fig. 1), extending to a convenient location for manipulation. It will be obvious that, by angular adjustment of the sleeve 85 and casing 69, the time when the contacts come into engagement may be varied and thereby the time when the liquid is injected into the combustion space relatively to the phase of operation of the engine may be controlled. Injection may thus be varied at will so as to take place during the intake stroke or during the compression stroke, or even, on occasion, so as to extend over into the expansion stroke.

Means is also provided to permit adjustment of the contacts individually so as to determine the instant of engagement of each pair of contacts independently of the others. Thus the contact 77 is shown as supported upon a screw, adjustable relatively to the contact support 70.

When the injection apparatus is employed in connection with a multicylinder engine, as shown, the pump members 31 for the several cylinders may be connected by the pipe fittings 38 to a common supply pipe 91 leading from a reservoir 92, which, if the apparatus be a part of the power plant of an automobile, will ordinarily be located at the rear end of the vehicle. A filter 93 and a pump 94 may be inserted in the supply line if desired. The pump may be of any type adapted to supply liquid at constant pressure, as, for example, such as is shown in my Patent No. 1,570,381. By the use of such a pump the pipes and several pumping chambers of the injectors may be filled with liquid independently of the operation of the injector magnets, and thus the priming or starting operation may be facilitated. If the pump be employed, it may be necessary, of course, to select for the valve spring 36 a spring sufficiently strong to hold the valve 34 closed against the pressure produced by the pump alone.

It is desirable that the passage leading from the tank to the point of delivery, and particularly the injector device and the passages leading therefrom, should be self-venting, i. e., that they should lead always upwardly so that no air pockets are formed to interfere with the operation of the injector mechanism.

In the operation of the apparatus, when starting the engine, since the valves all open

in the direction of the engine, the air may be removed from the pipes and the passages may be filled with liquid by utilizing the suction of the engine, the valve 20 being suitably positioned to restrict flow of air to the cylinders through the intake manifold. After the engine has been started thus, operating with fuel taken in by suction, and the injectors become filled with liquid, they will begin to operate to force liquid into the combustion chambers at the time determined by the breaker adjustment. Then the valve 20 may be partially or fully opened and fuller charges of air will be taken in at each intake stroke. The power developed upon the explosion stroke will vary with the quantity of fuel injected, i. e., with the duration of the injector action. Thus the adjustment of the casing 69 longitudinally of the spindle 65 will correspond with the usual operation of the "accelerator" in the throttle-controlled engine. Furthermore, by the angular adjustment of the breakers the injection may be made to take place at any desired piston position either on the intake stroke, thus operating upon the usual Otto cycle, or during the compression stroke, thus approaching more nearly operation upon the Diesel cycle.

Since the intake of air can be controlled by the air-supply limiting means, such as the valve 20, and the fuel supply can also be controlled as desired, it is possible to determine at will both the quantity and the quality of the charge. The valve spring 36 should, of course, be selected of such strength as not to permit too great flow, if any, of fuel during the induction stroke of the engine. By suitably controlling the quantity of air admitted and independently controlling the quantity of fuel injected thereinto the operator is therefore enabled to obtain, as desired, proper mixture for idling or low power conditions as well as to secure the proper amount of charge for the desired power output.

It will be noted that, by the means described, the pressure necessary to inject the liquid into the combustion chamber of the engine is applied to the liquid in the pressure chamber with minimum movement of the pumping mechanism, i. e., of the armature and bellows, and that the inertia of the moving parts is correspondingly low. Furthermore the moving parts may be made much lighter than would be possible with other types of pressure producing means. It will be noted also that the application of pressure and the release of pressure occur practically instantaneously upon the making and breaking of the magnet circuit, thus permitting very exact control both of the timing and of the duration of the application of pressure.

It will be understood that various changes may be made in the details of apparatus employed without departing from the spirit and scope of the invention, and therefore I do not

wish to be restricted to the features herein described except as required by the language of the appended claims in view of the prior art.

I claim:

1. An internal combustion engine having a combustion chamber, electromagnetically actuated pumping means for supplying liquid fuel thereto, and means for controlling the actuation of said pumping means comprising a circuit maker and breaker, means to vary the time of actuation of the circuit maker and breaker and means independent of the timing means for varying the duration of contact of the circuit maker and breaker. 70

2. An internal combustion engine having a combustion chamber, a pump for supplying liquid fuel directly thereto and means for controlling the actuation of said pump comprising a circuit maker and breaker and means 85 for varying the relation of the supply of current thereby to the phase of operation of the engine.

3. Structure as set forth in claim 2, the varying means comprising a cam having successively varying cam surfaces and means for shifting the circuit maker and breaker relatively to said cam. 90

4. An internal combustion engine having a plurality of cylinders, a liquid fuel pump 95 device for each cylinder, electromagnetic means for actuating each device, and means for controlling supply of current to said electromagnetic means comprising a circuit maker and breaker having a pair of contacts for each of said devices. 100

5. Structure as set forth in claim 4, the pairs of contacts being individually adjustable to determine the time of engagement.

6. Structure as set forth in claim 4, the contacts being arranged in an annular series and actuated by a central cam. 105

7. Structure as set forth in claim 4, the contacts being arranged in an annular series actuated by a central cam and being shiftable 110 angularly about the cam.

8. Structure as set forth in claim 4, means being provided to vary the duration of the period of engagement of the contacts.

9. Structure as set forth in claim 4, means being provided to vary the duration of the period of engagement of the contacts, said means comprising a tapered cam, the contacts being arranged to be actuated thereby and to be shifted axially of the cam. 115

10. A liquid injecting device comprising a pressure chamber having inlet and outlet passages and valves therefor, bellows communicating with said chamber, an armature connected to said bellows, and a coil surrounding said bellows and arranged to actuate the armature in a direction to contract the bellows. 125

11. Structure as set forth in claim 10, the 130

coil being provided with a short-circuited secondary coil.

12. An internal combustion engine having a combustion chamber, a passage adapted to supply liquid to said chamber, electromagnetic means for exerting pressure upon the liquid in said passage, and means the operation of which is synchronized with the engine movement for controlling flow of current to said electromagnetic means and for effecting injection of the fuel into said chamber by the action of said electromagnetic means, the current-controlling means comprising a circuit maker and breaker and means for varying the time of actuation of the circuit maker and breaker relatively to the movement of the driving means.

13. An internal combustion engine having a combustion chamber, a passage adapted to supply liquid fuel to said chamber, electromagnetic means for exerting pressure upon the liquid in said passage, and means the operation of which is synchronized with the engine movement for controlling flow of current to said electromagnetic means and for effecting injection of the fuel into said chamber by the action of said electromagnetic means, the current-controlling means comprising means for varying the duration of the period of supply of current to the electromagnetic means.

14. The combination with a pressure chamber to which liquid is to be delivered of means for supplying liquid thereto comprising an electromagnetic coil having a hollow core in the interior thereof, a bellows communicating with said chamber and positioned in said hollow core, and an armature for said coil connected to one end of said bellows to actuate the bellows by movement of the armature.

15. The combination with a fitting having a chamber to which liquid is to be delivered under pressure of a bellows communicating with said chamber and supported at one end upon said fitting, an electromagnetic coil surrounding said bellows and supported upon said fitting, and an armature for said coil connected to the free end of said bellows.

In testimony whereof I affix my signature.

JOHN M. LEA.
